UNITED STATES PATENT OFFICE.

CHARLES D. GOLDEN, OF CHICAGO, ILLINOIS.

DESIGN FOR A CLOCK-CASE.

SPECIFICATION forming part of Design No. 26,669, dated February 23, 1897.

Application filed January 16, 1897. Serial No. 619,492. Term of patent 3½ years.

To all whom it may concern:

Be it known that I, CHARLES D. GOLDEN, a citizen of the United States, residing at Chicago, in the county of Cook and State of Illinois, have invented and produced a new and original Design for Clock-Cases, of which the following is a specification, reference being had to the accompanying drawing, embodied in one figure, showing a front elevation of a clock-case, illustrating my design.

The principal feature of my design consists of the representation of a landscape in alto-rilievo in which the figure of a woman clothed in loose robes is shown in a recumbent posture, her left arm resting upon the ground, while the right arm is raised above her head in the act of waving the American flag. In the immediate foreground and at the base of the hill upon which she reclines is a railway-train, at the right a ship, and in the central foreground a globe, upon which stands an eagle with outstretched wings, the whole forming a setting for a central clock-face.

Referring to the drawing, *a* represents a clock-face which is immediately surrounded

by a circular beaded border *b*. The clock-face is represented as forming the central feature of a rocky cliff or mountain side, upon which the female figure *c* reclines. Her left arm is bent and her elbow rests upon the ground above the clock-face. Her right arm grasps the American flag, which hangs behind her. At her side lies a harp. At her feet a sheep is grazing upon the rugged hillside. At the left in the immediate foreground is seen a railway-train, at the right a ship upon the sea, while in the center foreground is shown a globe surmounted by an eagle with outstretched wings and grasping in his talons an olive branch and a bunch of arrows.

40

I claim—

The alto-rilievo design for a clock-case, substantially as shown and described.

In testimony whereof I have signed this specification, in the presence of two subscribing witnesses, this 23d day of December, 1896.
